(57) **CLAIM**

We claim the ornamental design for a sink, as shown and described.

DESCRIPTION

FIG. 1 is a perspective view of an embodiment of the claimed design;

FIG. 2 is a front view of the design shown in FIG. 1; FIG. 3 is a top view of the design shown in FIG. 1; FIG. 4 is a bottom view of the design shown in FIG. 1; FIG. 5 is a side view of the design shown in FIG. 1; FIG. 6 is another side view of the design shown in FIG. 1; FIG. 7 is a perspective view of another embodiment of the claimed design; FIG. 8 is a front view of the design shown in FIG. 7; FIG. 9 is a top view of the design shown in FIG. 7; FIG. 10 is a bottom view of the design shown in FIG. 7; FIG. 11 is a side view of the design shown in FIG. 7; FIG. 12 is another side view of the design shown in FIG. 7; FIG. 13 is a perspective view of another embodiment of the claimed design; FIG. 14 is a front view of the design shown in FIG. 13; FIG. 15 is a top view of the design shown in FIG. 13; FIG. 16 is a cross-sectional view of the design shown in FIG. 13 taken along line 16-16 in FIG. 15; FIG. 17 is a cross-sectional view of the design shown in FIG. 13 taken along line 17-17 in FIG. 15; FIG. 18 is a cross-sectional view of the design shown in FIG. 13 taken along line 18-18 in FIG. 15; FIG. 19 is a cross-sectional view of the design shown in FIG. 13 taken along line 19-19 in FIG. 15; FIG. 20 is a perspective view of another embodiment of the claimed design; FIG. 21 is a front view of the design shown in FIG. 20; FIG. 22 is a rear view of the design shown in FIG. 20; FIG. 23 is a side view of the design shown in FIG. 20; FIG. 24 is another side view of the design shown in FIG. 20; FIG. 25 is a top view of the design shown in FIG. 20; FIG. 26 is a bottom view of the design shown in FIG. 20; FIG. 27 is a cross-sectional view of the design shown in FIG. 20 taken along line 27-27 in FIG. 25; FIG. 28 is a cross-sectional view of the design shown in FIG. 20 taken along line 28-28 in FIG. 25; FIG. 29 is a cross-sectional view of the design shown in FIG. 20 taken along line 29-29 in FIG. 25; and, FIG. 30 is a cross-sectional view of the design shown in FIG. 20 taken along line 30-30 in FIG. 25.
The ornamental design which is claimed is shown in solid lines in the drawings. The broken lines in the drawings are for illustrative purposes only and form no part of the claimed design. Broken lines formed by equal length dashes (i.e., (Continued)

dash-dash) show unclaimed portions of the design. Broken lines formed of unequal length dashes (i.e., dash-dot) show unclaimed boundaries between claimed and unclaimed portions of the design.
